United States Patent Office.

CHARLES C. JOHNSON, OF SPRINGFIELD, VERMONT.

Letters Patent No. 88,174, dated March 23, 1869.

TOY-HOOP.

The Schedule referred to in these Letters Patent and making part of the same.

To all whom it may concern:

Be it known that I, CHARLES C. JOHNSON, of Springfield, in the county of Windsor, and the State of Vermont, have invented a new and useful Improvement in Toy-Hoops; and I do hereby declare that the following is a full and exact description thereof, reference being had to the accompanying drawings, and to the letters of reference marked thereon.

The nature of my invention consists in the application of bells to the spokes, or handle of a hoop, which are struck by hammers operated by the hoop as it revolves, in such a manner as to make a succession of musical sounds, or chords, or to play a tune; and also in a method of preventing the revolution of the hoop in the wrong direction.

Figures 1 and 2 are side views of different arrangements of my hoop.

Figure 3 is a section through the handle, showing the action of the hammer upon the bell, and the operation of the retaining-spring for preventing the backward revolution of the hoop.

Figure 4 is a detached side view of the spring-hammer and bell.

Like letters of reference indicate corresponding parts in all the figures.

In fig. 1, the bells *a* and hammers *b* are arranged side by side on the handle *c*.

The bells are acted upon by pins *d*, affixed to the spokes *e* of the wheel, and which project therefrom, the action of which is better shown in figs. 3 and 4.

The spring *f* is for preventing the backward revolution of the wheel, which, if allowed, would distort and bend the springs of the hammers from their proper position.

Fig. 2 is an arrangement in which the bells and hammers are placed upon the spokes, and are operated by pins *d*, affixed to the handle.

In fig. 3, the bells are affixed to the handle, which

is forked at the end to allow the hoop and spokes to pass between it.

The operation of the retaining-spring is as follows:

After the spoke *e* has passed the spring *b*, which it operates by means of the pin *d*, it comes in contact with the spring *f*, and passes it by, pushing it aside. The spring then returns to its former position, presenting a direct resistance to the return of the spoke, should the hoop be revolved in the wrong direction.

In fig. 4, the pin *d*, affixed to the spoke, is shown just coming in contact with the spring *b*, to which the hammer is attached, and which, as the hoop revolves, will be released and strike the bell.

Any number of bells may be employed, and the spokes may be made of a curved form, to enable the bells to be struck in succession as the hoop revolves.

The bells may be differently toned, and the pins arranged in such relative positions on the spokes, as to strike in succession, and at such intervals as will play a tune, or they may be arranged to strike together, in a chord.

The bells can be attached to either or both sides of the handle or spokes, as required.

What I claim as my invention, and desire to secure by Letters Patent, is—

1. The application, to a toy-hoop, of a series of bells, in such a manner as to be struck successively, or in unison, by the operation of spring-hammers, actuated by pins brought into juxtaposition by the revolution of the hoop, substantially as set forth.

2. In combination therewith, the retaining-stop *f*, for preventing the backward rotation of the hoop, substantially as described.

In witness whereof, I have hereunto signed my name, in the presence of two subscribing witnesses.

Witnesses: CHARLES C. JOHNSON.

D. M. SMITH,
G. W. KINGSLEY.
